UNITED STATES PATENT OFFICE.

JOSEPH B. MOWRY, OF CLEVELAND, OHIO.

WATER-HEATER.

1,108,607.

Specification of Letters Patent. Patented Aug. 25, 1914.

Application filed February 17, 1913. Serial No. 748,790.

To all whom it may concern:

Be it known that I, JOSEPH B. MOWRY, a citizen of the United States, and resident of Cleveland, in the county of Cuyahoga and State of Ohio, have invented certain new and useful Improvements in Water-Heaters, of which I hereby declare the following to be a full, clear, and exact description, such as will enable others skilled in the art to 10 which it appertains to make and use the same.

The objects of the invention are to provide a simple and efficient form of water heater which is characterized by practicability in 15 construction and slight initial cost and in which the water is continuously and repeatedly exposed to a heating medium, and the heating surface is most efficiently disposed to obtain quick results.

20 The device is adapted for use as an "instantaneous" water heater for all domestic uses, and also can be employed in a hot water circulating system for heating a dwelling house, or other edifice.

25 The invention comprises a series of hollow water heating units having a central means for communicating with each other and inclosed in a non-radiating casing in which a non-conductor such as asbestos is 30 inclosed. These units are superimposed above each other in staggered relation and separated by passages for circulation of the heating medium.

The construction and arrangement of the 35 several units and means for connecting and heating the same as hereinafter more fully described, shown in the accompanying drawings and specifically pointed out in the claims.

40 In the accompanying drawings Figure 1 is a vertical central section of the device; Fig. 2 is a transverse section on line *a*—*a* Fig. 1; Fig. 3 is a transverse section on line *b*—*b* Fig. 1. Fig. 4 is a vertical section of a casing showing the construction arranged to prevent radiation of heat therefrom.

45 In these views A is the casing preferably formed of two thin sheet metal tubes, inclosing plates B, B of corrugated sheet asbestos which efficiently prevent the outward radiation of heat.

C, C are burners employed for supplying a current of hot air to the heater, but any 55 other heating device can be readily employed for this purpose.

D is the lowest hollow water heating unit into which the water flow is led at one extremity at E. This unit comprises a flattened tube provided with a vertical fork 60 shaped partition the stem portion F of which is placed upon the center line of the unit and preferably spaced from the inlet opening thus permitting the water to flow equally on both sides of it. The sides 65 F', F' of the forked extremity extend nearly to the opposite end of the unit leaving a space at their ends and between them for flow of water; substantially centrally placed in the upper wall of the unit in the crotch of 70 the forked partition is the upwardly directed outlet opening G and a short tube or union connects this opening with the unit H above. In this manner the water is first compelled to flow the entire length of the 75 unit and to return between the forks to the central outlet, thus giving it two exposures to the heated surface of bottom and sides of the unit and raising the temperature quickly before it flows upward to 80 the next unit. The units superimposed upon the lowest unit provide for a return circulation in a somewhat different manner, as follows: A vertical partition H runs through this hollow unit and is arranged on two 85 vertical planes, connected together by a transverse and preferably S shaped member H' at the center of the unit. Upon one side of this S shaped partition in the bottom of the unit is located the inlet opening 90 I leading from the opening G below and at the other side is located the outlet opening J in the top plate of the unit, which leads to the unit above. The water entering the unit from below through the opening I 95 must divide its flow and pass entirely around both ends of the vertical partition which are spaced from the end walls of the unit at K, K to provide passages for this purpose. The water then flows back from the ends to 100 the outlet opening on the other side of the partition. Each unit above is constructed in substantially the same manner, and the upper and lower walls of the units are preferably horizontal to equalize the flow over 105 all parts of the units, so that no portion of the water can be heated to a higher degree of temperature than another. The complete and continuous circulation of the water thus afforded throughout the heater 110 and the repeated flow through each unit insures raising the water quickly to a high

degree of temperature, and if heat should be irregularly applied to the bottom of any one unit the water must all traverse the entire surface of each bottom and a uniform 5 degree of temperature will result. The water will rise as it becomes hotter and thus permit the entrance of cold water as fast as it is drawn off from above. These units bear a staggered relation to each other 10 at their ends thus providing a tortuous passage L for the heated products of combustion, which is applied directly throughout the length of each unit. A flue M conducts away the products of combustion, and 15 is preferably attached to the cover or hood. Small blind stays O, O may be employed to prevent warping of the units and connect the upper and lower walls. Openings P, P are shown placed opposite to each 20 other to introduce a cleaning tool. These openings are screw threaded so that stoppers or plugs of any character can be inserted in them.

Having described the invention what I 25 claim as new and desire to secure by Letters Patent is:

1. In a water heater, a bottom unit comprising a hollow chamber, provided with an inlet opening at one end, and a central outlet opening in its upper wall, and a vertical forked partition longitudinally disposed in said chamber, and having the extremities of the stem end and forks spaced from the end walls of the chamber, the stem end adjacent 30 to the outlet opening, and water heating units superimposed above said bottom unit, said superimposed units provided with vertical longitudinal partitions spaced at their ends from the ends of the chamber, and provided with inlet and outlet openings on opposite sides of said partitions and an inclosing casing for all said units.

2. In a water heater, a casing, a heat supplying device, and a series of superimposed 45 horizontal staggered hollow water units within said casing separated to form a circulating passage for the heating medium, the lower unit provided with a water inlet at one end, and with a substantially central outlet opening in its upper wall, said lower unit having a vertical fork shaped partition therein, the sleeve of the fork adapted to divide the water flow into equal portions at the sides of the unit, and the branches of 50 55 the fork adapted to receive the flow from the said sides and return same to the outlet opening, the upper units provided each with a vertical portion extending in different planes on each side of its longitudinal cen-

ter, and connected by a transverse partition 60 and having its inlet and outlet openings arranged one on each side of said transverse portion, whereby the flow of water is first directed longitudinally of the unit toward its ends, and afterward is returned toward 65 the center thereof, the outlet opening of one unit communicating with the inlet opening of the next adjacent unit.

3. In a water heater, a bottom unit comprising a closed chamber having an inlet 70 opening at one end and an outlet opening in its upper wall, and a forked partition in said chamber, having its extremities spaced from the end walls of said chamber, and having the stem end of the forks adjacent to the 75 inlet opening of the chamber, the said outlet opening being arranged between the forked extremities of said partition.

4. In a water heater, in combination, a closed bottom chamber having an inlet opening for water at one end and an outlet opening in its upper wall, and provided with a forked partition spaced at its ends from the 80 end walls of the chamber and having its stem end adjacent to and in line with the 85 inlet opening, the forks of said partition inclosing the outlet opening, and a second chamber superimposed upon said bottom chamber, said second chamber provided with a longitudinal partition spaced from the end 90 walls of said chamber, and with inlet and outlet openings arranged on opposite sides of said partition, the inlet opening in the second chamber communicating with the outlet opening in the bottom chamber.

5. In a water heater, a water circulating unit comprising a closed chamber having an inlet opening in the bottom and an outlet opening in the top, said openings being spaced apart, a transverse partition in said 100 chamber separating said openings, and vertical partition walls extending longitudinally from the ends of said partition, and having their outer ends spaced from the end walls of said chamber.

6. In a water heater, a water distributing and circulating chamber, said chamber provided with spaced openings in its upper and lower walls, and a partition separating said 105 openings, and extending partially to the end walls of said chamber.

In testimony whereof, I hereunto set my hand this 11 day of January, 1913.

JOSEPH B. MOWRY.

In presence of—

W. M. MONROE,
P. BREDEL.
